UNITED STATES PATENT OFFICE.

WILLIAM FRANKLIN, OF NEW HAVEN, CONNECTICUT.

FILTER.

SPECIFICATION forming part of Letters Patent No. 372,530, dated November 1, 1887.

Application filed June 13, 1887. Serial No. 241,182. (No model.)

To all whom it may concern:

Be it known that I, WILLIAM FRANKLIN, of New Haven, in the county of New Haven and State of Connecticut, have invented a new Improvement in Filters; and I do hereby declare the following, when taken in connection with the accompanying drawings and the letters of reference marked thereon, to be a full, clear, and exact description of the same, and which said drawings constitute part of this specification, and represent, in—

Figure 1, a vertical central section through the filter, the faucets, for convenience, being shown in the same plane; Fig. 2, an edge view of a single filtering-disk; Fig. 3, a modification in the filter.

This invention relates to an improvement in filters which are adapted for water-supply, and particularly to that class which are applied at the point of discharge, or where the water is drawn for use, the object of the invention being to construct the filter so that it will be self-cleansing while in operation and without stopping the ordinary flow or discharge, in contradistinction to that class of filters which are cleansed by reversing the filter, so as to cause the water to flow in the opposite direction through the filter.

A represents the base, through which is a central inlet-passage, B, and with which the supply-pipe C is connected. In the base is a chamber, D, separated from a chamber, E, above by a plate or diaphragm, F. The inlet B opens from the base into the chamber E through the diaphragm F. Around the outer edge of the diaphragm or partition, between the chambers D and E, is a downward passage, a. This may be in the form of numerous perforations, or may be an annular opening, but so that some portion of the water which passes through the inlet into the chamber E above the partition F may escape through the openings a to the chamber D below. From the chamber D is an outlet, G, preferably provided with a faucet, H, so that the water which escapes from the chamber E downward into the chamber D may be drawn off through the passage G.

In the chamber E, above the partition F, several metallic disks, I, are arranged, preferably of concavo-convex shape, and corresponding to the upper surface of the partition F,

which presents the convex surface upward. The metallic disks I are of perforated metal, or made from woven wire, and are preferably corrugated radially, as seen in Fig. 2, the corrugations dying out at the center. These disks are secured together at the center, but so as to leave free space between the disks. This is best done by interposing small disks or collars between the disks at the center. The disks in diameter correspond to the diameter of the chamber E, and form the first or preliminary filtration. The convex side of the disks is upward, so that the tendency of the water may be naturally to flow toward the wall of the chamber E.

Above the chamber E is a filtering-chamber, J. This chamber is formed by a cylinder, K, of less external diameter than the internal diameter of the casing L. The casing extends upward from the base. The cylinder K is screwed into the base, so that it may be removable therefrom.

The cylinder K is provided with a diaphragm, M, at its lower end, and a similar diaphragm, N, at its upper end, which are perforated or made from woven wire. This chamber is filled with any suitable filtering material, not necessary to be particularly described, as suitable filtering materials are well known.

Above the filtering-chamber J is a chamber, O. The cylinder K, being of less diameter than the casing, leaves an annular space or passage, b, between the cylinder K and the casing, and from this passage b passages d in the base lead into an annular chamber, P, in the base, which is outside the chamber D, but separated therefrom. From the chamber P a passage, R, leads to an outlet or faucet, S, here shown as in the base directly opposite the faucet H.

Water having passed up through the filtering-disks I, thence through the filtering-chamber J, thence into the chamber O above, may escape therefrom downward through the passage b, around the filtering-chambers J and E, into the annular space P below, and thence be drawn off through the second faucet S.

In the chamber O, above the first filtering-chamber, is a second series of concavo-convex disks, T, of like construction with the disks I below, but of finer mesh or perforations. These disks correspond to the diameter of the cham-

ber O, and are supported therein. From the chamber O, above the disks T, an outlet is preferably made through a faucet, U, by which water which has passed through the filtering-disks T may be drawn off, if desirable.

Above the chamber O is a second chamber, V, filled with filtering material, which should be of a grade finer than the chamber J below. The casing L extends above the filtering-chamber, and so as to form a discharge-chamber, W, which communicates with an outlet-faucet, Y. This completes the construction of the filter. If the faucets below the upper faucet Y be closed, the passage of the water is through the disks I, through the chamber J, thence through the disks T, then through the chamber V, and finally to be drawn off through the faucet Y, the filtering being perfected by the different grades of filtering materials, and so that at its final discharge the water is perfectly filtered.

The first filtration is produced by the metal disks I, where the coarser or larger foreign substances will be retained or arrested. The next filter, J, will separate other foreign matters which may escape the disks I; then the finer disks T come into action and arrest certain portions of the foreign matter which may have escaped the filtering materials below; and, finally, the last filtering-chamber, V, removes all foreign matters which may have been in the water. Now, if in drawing through the faucet G the faucet H be opened, so as to permit a small escape of the water, the portion of the water which passes into the chamber E will be permitted to escape downward through the chamber D to the faucet H, and this downward flow of the water washes, as it were, the under surfaces of the disks where the foreign substance has been arrested, and will cause that substance to pass off through the chamber D to the faucet H, and this downward flow of the water from the disks through the outlet G will keep the disks I thoroughly cleansed from the foreign substances which would otherwise lodge and be retained therein.

The corrugated shape of the disks permits a ready flow of the water between the disks, and, in fact, directs that flow to the outer edge of the disks, where the escape of the water is made easy into the discharge-chamber D below.

The flow of water into the chamber E also cleanses the under surface of the diaphragm M of the filtering-chamber J. Thus while a flow is permitted from the chamber D the filtering-chamber E is maintained in a thoroughly cleansed condition; but while this cleansing operation is going on water continues to flow through the filter and out through the faucet Y, the amount required for cleansing not materially affecting the flow of water through the faucet Y, under an ordinary water-supply. The same cleansing operation in the chamber O is produced by the water which has passed through the filter J, so that if the escape or faucet S be open the inflow of the water will wash, as it were, the surfaces of the disks T

and the under surface of the filtering-chamber V. The product of such washing passes down through the passage b to the outlet R, where it is drawn off through the faucet S. This cleansing may, and should, also be in operation when drawing the perfectly-filtered water through the faucet Y. I say should be in operation, because being so open it maintains the surfaces of the disks and filtering-chambers always in a thoroughly cleansed condition, and avoids the passage of the water through the foreign substances, which might otherwise remain upon the said surfaces to the detriment of the water.

If at any time water without being filtered is desired, it may be drawn off through the faucet H. Again, if water which has been partially filtered is desired, then it may be drawn off through the faucet U, which opens from the chamber O above the disks T.

In some cases the cleansing above the first filtering material may be unnecessary. In that case the faucet S and its communicating chamber and passages will be omitted, as seen in Fig. 3; and if the final purification of the water is not desirable the filter-chamber V, as also the disks T, may be omitted, as seen in Fig. 3.

In cases where large quantities of water are to be filtered, as for paper-mills, hotels, breweries, &c., the filter may be arranged between the main supply-pipe and the distributing-pipes. In that case the distributing-pipes will take the place of the faucet Y; and under such arrangement the faucets H and S, if S be used, should remain open to some extent so as to insure a constant cleansing of the filter, and this is accomplished without interfering with the general supply to the distributing-pipes through the filter under ordinary water-pressures.

A good and desirable result, so far as cleansing the filter is concerned, will be attained without the disks I in the chamber E below the filtration-chamber J, as seen in Fig. 3. The rush of water into the chamber will cause such an agitation of the water as to constantly remove any foreign substance which would naturally collect upon the under side of the diaphragm M, and this material will find its escape down into the chamber D, and thence off to waste through the passage G.

I have stated that the filtering-disks may be made from perforated metal or woven wire; but by the term perforated metal I wish to be understood as embracing either, as may be desired.

By this construction of filter the filter is, if desirable, constantly cleansed while in use, or may be cleansed at any time without return or changing the direction of the water through the filtering-chambers.

I claim—

1. A filter consisting of a chamber, D, a second chamber, E, above said chamber D, but communicating therewith, a water-supply passage opening upward through the partition between the said chambers D and E, an out-

let-passage, G, from said chamber D, a filtering-chamber, J, above said chamber E, supplied with filtering material, and an outlet above said filtering-chamber J, through which 5 water may be drawn, substantially as described.

2. In a filter, the combination of a chamber, D, a chamber, E, above said chamber D, an inlet-passage opening upward through the bottom of the chamber E, an outlet-passage from 10 said chamber D, a series of metallic perforated disks in said chamber E, and in diameter corresponding to the diameter of the said chamber, an opening through the bottom of the chamber E into the chamber D below, a filtering-chamber, J, above said chamber E, and an 15 outlet above said filtering-chamber J, substantially as described.

3. The combination, in a filter, of a chamber, D, a chamber, E, above said chamber D, 20 the upper surface of the bottom of said chamber E presenting a convex shape, one or more openings near the outer wall of the said chamber E into the chamber D below, a supply-passage opening upward through the bottom of the chamber E into said chamber, the escape-passage G from the chamber D, a 25 series of concavo convex perforated disks in said chamber E, the convex side up, and a filtering-chamber, J, above said chamber E, with 30 an outlet above said filtering-chamber J, substantially as described.

4. The combination of a chamber, D, a chamber, E, above said chamber D, openings through said chamber E down into the chamber D below, an upward water-supply passage 35 through the bottom of the said chamber E, and the outlet-passage G from said chamber D, a filtering-chamber, J, above said chamber E, a second filtering-chamber, V, above said chamber

ber J, with the chamber O between the said 40 two filtering-chambers, a second escape-passage, R, with downward passages leading from the chamber, intermediate between the two filtering-chambers, to said escape-passage R, substantially as described.

5. The combination of the chamber D, a chamber, E, above it, a water-inlet passage opening upward into said chamber E through its bottom, an open passage through the bottom of said chamber E into the chamber D 50 below, an escape-passage, G, opening from the said chamber D, a filtering-chamber, J, above said chamber E, a chamber, O, above said filtering-chamber J, an escape-passage, R, below said chamber O, with openings from the chamber O into said escape-passage R, metallic perforated disks in said chamber O, but above the passage from said chamber to the escape-passage R, and a draw-off passage above said 55 disks, substantially as described.

6. The combination of the chamber D, the chamber E above it, a water-supply passage opening into said chamber E through its bottom, an escape-passage from said chamber E down into the chamber D, an outlet-passage 65 from said chamber D, two filtering-chambers, J and V, above said chamber E, with a chamber, O, between said filtering-chambers, an escape-passage, R, below said chamber O, with passages leading from said chamber O to said 70 escape-passage R, and the outlet or draw-off above said filtering-chamber V, substantially as described.
